(57) **CLAIM**

I claim the ornamental design for a mirror with stand, as shown and described.

DESCRIPTION

FIG. 1 is a front view of a mirror with stand showing my new design;

FIG. 2 is a side view thereof;

FIG. 3 is a back view thereof; and,

FIG. 4 is a perspective view thereof.

The broken lines are for the purpose of illustrating portions of the mirror with stand, which form no part of the claimed design.
